[57] ABSTRACT

A unidirectional microphone windscreens which includes portions formed of compressed foam and uncom-pressed foam located on opposite sides of the capsule to enhance directivity of the microphone.

3 Claims, 3 Drawing Figures

Fig. 1

Fig. 3

Fig. 2

MICROPHONE WINDSCREEN

SUMMARY OF THE INVENTION

This invention relates to an external microphone windscreens which improves directivity of the microphone.

The microphone windscreens of this invention is formed of material of two different densities. The front portion of the screen into which a person speaks is formed of uncompressed foam while the rear portion of the screen behind the cartridge is formed of a higher density compressed foam. This construction allows the blocking of low frequency sounds through the back of the microphone and improves the front to back discrimination of the microphone. Examples of microphones which have utilized foam to reduce wind noise are seen in U.S. Pat. Nos. 2,536,261; 4,410,770; 2,520,706; 3,154,171 and British Pat. No. 855,972.

Accordingly, it is an object of this invention to provide for an improved windscreens which is for a microphone.

Another object of this invention is to provide for a microphone windscreens which improves directivity of the microphone.

Another object of this invention is to provide for a microphone windscreens which acts as an acoustic absorber at high frequencies.

Other objects of this invention will become apparent upon a reading of the following description.

BRIEF DESCRIPTION OF THE DRAWINGS

FIG. 1 is a perspective view of a unidirectional microphone incorporating the windscreens of this invention.

FIG. 2 is a cross-sectional view of the microphone of FIG. 1.

FIG. 3 is a sectional view of an alternative windscreens for a hand-held microphone.

DESCRIPTION OF THE PREFERRED EMBODIMENTS

The preferred embodiments herein described are not intended to be exhaustive or to limit the invention to the precise forms disclosed. They are shown and described to explain the principles of the invention and its application and practical use to enable others skilled in the art to utilize the invention.

FIGS. 1 and 2 depict a unidirectional microphone 10 which includes a conventional unidirectional microphone cartridge or capsule 12. Microphone capsule 12 includes the sound reproducing elements and is connected to a suitable amplification source (not shown). Enclosing capsule 12 is a windscreens 14 seated between housing posts 15. Windscreens 14 which includes an

outer layer 16 preferably formed of wire mesh. The inner layer 18 of windscreens 14 includes a front portion 20 positioned spacedly in front of the sound receiving entry 22 of capsule 12 and a rear portion 24 positioned spacedly at the opposite side of the capsule. Inner layer front portion 20 is formed of an uncompressed foam material such as polyurethane. Inner layer rear portion 24 is formed of a compressed foam material such as polyurethane.

Windscreens 14 functions as follows. As a person speaks into microphone 10 in the direction shown by arrow 26, sound travels through windscreens inner layer front portion 20 to capsule 12. The uncompressed foam of front portion 20 allows sound waves to pass readily through to capsule 12. The compressed foam of windscreens inner layer rear portion 24 prevents low frequency sounds from entering through the screen rear portion and also absorbs some high frequency sounds to improve front-to-back discrimination of the microphone.

An alternative microphone construction 28 shown in FIG. 3 involves a unidirectional capsule 30 similar to capsule 12, mounted on a handle 32. A windscreens 34 having a portion 36 of uncompressed foam is positioned spacedly in front of the capsule sound receiving entry 38 and a portion 40 of compressed foam is positioned spacedly at the opposite side of the capsule. As with microphone 10, the windscreens 34 of microphone 28 improves the front-to-back discrimination of the microphone by blocking certain low frequency sounds and absorbing high frequency sounds at windscreens portion 40.

It is to be understood that the invention is not limited to the details above-given, but may be modified within the scope of the appended claims.

I claim:

1. In a unidirectional microphone, said microphone including a unidirectional capsule having a sound receiving entry, a windscreens positioned adjacent to said microphone capsule, the improvement wherein said windscreens includes a first portion formed of uncompressed cellular material positioned in front of said capsule sound receiving entry and a second portion formed of compressed cellular material positioned to the rear of said capsule opposite its sound receiving entry, said windscreens second portion constituting means for blocking and absorbing sound waves wherein the directivity of said microphone is enhanced.

2. The windscreens of claim 1 wherein said compressed cellular material is compressed polyurethane foam.

3. The windscreens of claim 2 wherein said uncompressed cellular material is uncompressed polyurethane foam.
